UNITED STATES PATENT OFFICE.

GEORGE TSOBANACOS, OF NEW YORK, N. Y.

SOUNDING WHEELED TOY.

Application filed February 1, 1928. Serial No. 251,122.

The present invention relates to improvements in toys and has reference more particularly to a sounding wheeled toy.

One of the important objects of the present invention is to provide a toy that includes a wheeled body, a pair of pivoted knockers being mounted for vibratory movement on the body, said body including an impact face portion that is struck by the knockers, additional means being provided whereby said knockers will be actuated intermittently as the toy is propelled along the surface.

A further object is to provide a sounding wheeled toy of the above mentioned character which is simple in construction, inexpensive, strong and durable and further well adapted to the purpose for which it is designed.

Other objects and advantages of the invention will become apparent during the course of the following description when taken in connection with the accompanying drawing.

In the accompanying drawing wherein like reference characters indicate corresponding parts throughout the several views:

Figure 1 is a side elevation of the sounding wheeled toy embodying my invention.

Figure 2 is a top plan view thereof, and

Figure 3 is a transverse section through the body of the toy showing the rear axle and the knocker engaging fingers carried thereby.

In the drawing wherein for the purpose of illustration is shown the preferred embodiment of my invention, the numeral 1 designates generally the body of the toy, the same comprising a pair of parallel spaced side walls 2 and 3, respectively, on the top of which is secured the top wall 4. The top 4 is formed with a pair of longitudinally extending parallel spaced slots 5 and 6 respectively in the intermediate portion thereof and the purpose of these slots will be hereinafter more fully described.

Front and rear axles 7 and 8, respectively, are formed at their ends with the reduced cylindrical pintles 9 that extend through suitable openings provided therefor in the sides 2 and 3 adjacent the forward and rear ends of the body and surface engaging wheels 10 are secured on the outer ends of the respective pintles in the manner as clearly illustrated in the drawing. Each axle is of substantially rectangular shape in cross section as indicated by the dotted lines in Figure 1, and the rear axle 8 is formed with a pair of

transversely extending slots adjacent the respective ends thereof, one of the slots being disposed at right angles with respect to the other as indicated very clearly in Figure 3, 60 and these slots are designated by the numerals 11 and 12 respectively.

An elongated finger in the form of a strip extends through the slot 11, and has its intermediate portion secured in said slot by a transverse pin 14 so that the respective ends of the finger extend beyond the opposite sides of the rectangular rear axle 8.

A similar finger 15 extends through the slot 12 which is disposed at right angles with respect to the slot 11 and the intermediate portion of the finger 15 is secured to the rear axle 8 by a suitable locking pin similar to the pin 14 associated with the aforementioned finger 13. In this manner the fingers 13 and 15 75 will be disposed at right angles with respect to each other.

The present invention further comprehends the provision of a pair of elongated arms 16 and 17 respectively that are pivotally secured 80 adjacent their lower ends on a cross rod 18 that extends between the sides 2 and 3 of the body 1 forwardly of the rear axle 8, the lower ends of the arms or levers being disposed in alignment with the respective fingers and further so located as to be within the path of movement of the fingers.

These arms or levers extend upwardly through the respective slots provided therefor in the top 4 and carry at their upper free 90 ends the knocker forming heads 19 and 20 respectively, which strike the upper face of the forward end portion of the top 4 which portion of the top provides what I term as an impact face forming portion denoted by the 95 numeral 21.

A pull string 22 is attached to the forward end of the wheeled body 1 in the manner as shown in Figure 1 whereby the toy may be propelled upon the floor.

It will be readily obvious that as the toy moves along the surface, the fingers 13 and 15 carried by the rotatable rear axle 8 will strike the lower ends of the respective pivoted arms whereby to intermittently swing the upper ends of the arms upwardly and after the fingers have moved out of engagement with the lower ends of the respective pivoted arms, the knocker heads will strike the impact face portion 21 thus producing a sound.

A sounding wheeled toy of the above mentioned character will afford considerable

amusement to small children, and due to its simplicity, the same will at all times be positive and efficient in its operation. Furthermore, a sounding wheeled toy of the above 5 mentioned character can be manufactured at a very low cost and will also be strong and durable.

While I have shown the preferred embodiment of my invention it is to be understood 10 that minor changes may be made therein without departing from the spirit of the invention and the scope of the appended claim.

Having thus described the invention, what I claim as new is:—

15 In a toy of the class described, a body including spaced side walls, and a top wall, front and rear rotatable axles extending through the side walls, ground engaging wheels on the outer ends of the respective 20 axles, said top being formed with a pair of parallel spaced longitudinally extending slots in the intermediate portion thereof, the forward portion of the top providing an impact face, a rod extending transversely beneath

the top wall forwardly of the rear axle, a pair 25 of vertically disposed arms arranged in the respective slots and being pivoted, adjacent their lower ends on said transverse rod, knocker heads formed on the upper ends of the arms for cooperation with the impact 30 face portion of the top wall of the body, the rear axle being provided with a pair of slots, one of said slots being disposed at right angles 35 with respect to the other, a finger forming strip extending through each slot in the rear axle, and having its intermediate portion fixedly secured therein, said strips being adapted to intermittently engage the pivoted ends 40 of the respective arms to raise the knocker heads upwardly, said knocker heads being adapted to strike the impact face portion of the top when the strips are moved out of engagement with the pivoted ends of the arms 45 during the propulsion of the toy along the surface.

In testimony whereof I affix my signature.

GEORGE TSOBANACOS.
